UNITED STATES PATENT OFFICE.

LUTHER E. BERKEY, OF NEW YORK, N. Y.

TRAY ATTACHMENT FOR BEDSTEADS.

1,232,757.

Specification of Letters Patent. Patented July 10, 1917.

Application filed May 15, 1916. Serial No. 97,718.

To all whom it may concern:

Be it known that I, LUTHER E. BERKEY, a citizen of the United States, residing at New York city, in the county of Bronx, State of New York, have invented certain new and useful Improvements in Tray Attachments for Bedsteads; and I do hereby declare the following to be a full, clear, and exact description of the invention, such as will enable others skilled in the art to which it appertains to make and use the same.

The present invention is directed to improvements in tray attachments for bedsteads, and has for its object to so construct a device of this character that it can be easily and quickly attached to either side rail of the bedstead.

A further object of the invention is to provide a device of this character so constructed that the tray can be moved from its operative position to its inoperative position, when desired.

A still further object of the invention is to provide a tray which can be adjusted vertically and is capable of being swung to a position to suit the comfort of the occupant of the bed.

With these and other objects in view, this invention resides in the novel means of construction, formation and arrangement of parts to be hereinafter more fully described, claimed and illustrated in the accompanying drawing, in which:—

Figure 1 is a side elevation of the device.

Fig. 2 is a vertical sectional view through the device.

Fig. 3 is a sectional view on line 3—3 of Fig. 1.

Fig. 4 is a vertical central sectional view through the device showing the tray in its inoperative position.

Fig. 5 is a sectional view on line 5—5 of Fig. 1.

Fig. 6 is a detail perspective view of the disk.

The device consists of a tube 1, having its lower end terminating in a bracket 2, having engaged therewith a clamping screw 3 which is adapted to engage one of the side rails 4 of the bed. Carried by the bracket is a plate 5 which also engages the rail 4 and serves in conjunction with the bracket 2 to hold the tube 1 clamped in a vertical position to the bed rail.

Engaged in the tube 1 is a stem 6, said stem being held in adjusted positions by the set screw 7 which is carried by the tube 1. The upper end of the stem 6 terminates in a disk 8, said disk having carried by its upper surface a dove-tailed rib 9, one end of which projects beyond the periphery of the disk, and is provided with a perforation 10, the purpose of which will appear later.

The tray 11 may be of any suitable shape and has its under surface provided with a dove-tailed groove 12, one end of which opens into the recess 13, and projecting into the recess is a stud 14.

Associated with the disk 8 is a set screw 15 which passes through the rib 9 and is adapted to engage the base of the groove 12 so that the tray 11 can be held in adjusted positions.

Since the groove 12 is slidably engaged with the rib 9 it is obvious that when it is desired to move the tray to a vertical position that the same is slid to the right, as shown in Fig. 1, until the rib 9 is disengaged from the groove 12, after which the tray can be positioned vertically so that the stud 14 will engage the perforation 10, as clearly shown in Fig. 4 of the drawing.

What is claimed is:—

A device of the class described comprising a tube, means for detachably connecting said tube to a support, a stem adjustably connected to said tube and having a disk carried by its upper end, a rib carried by the upper surface of said disk and having a perforation in one end, a tray having a groove formed therein and slidably interlocked with said rib, said groove having one of its ends opening into a recess formed in said tray and its other end opening out upon the opposite edge of said tray, a stud carried by said tray and extending into said recess and adapted to engage in the perforation in said rib whereby a wall of said recess will engage said rib and support the tray in a vertical position.

In testimony whereof, I affix my signature, in the presence of two witnesses.

LUTHER E. BERKEY.
